DESIGN FOR TOOTH POWDER APPLIER

Lee O. Waller, Philadelphia, Pa.

Application November 1, 1934, Serial No. 53,839

Term of patent 14 years

To all whom it may concern:

Be it known that I, Lee O. Waller, a citizen of the United States, residing at Philadelphia, in the county of Philadelphia and State of Pennsylvania, have invented a new, original, and ornamental Design for a Tooth Powder Applier, of which the following is a specification, reference being had to the accompanying drawing, forming a part thereof.

Referring to the accompanying drawing, Figure 1 is a perspective view of the tooth powder applier showing the new design.

Fig. 2 is a sectional view in elevation taken on line a—a in Figure 1.

I claim:

The ornamental design for a tooth powder applier, substantially as shown.

LEE O. WALLER.
